(57) **CLAIM**

We claim the ornamental design for an accessory for hair styling and hair care apparatus, as shown and described.

DESCRIPTION

The patent or application file contains at least one drawing executed in color. Copies of this patent or patent application publication with color drawings will be provided by the office upon request and payment of the necessary fee.

FIG. 1 is a top perspective view of an accessory for hair styling and hair care apparatus showing our new design; FIG. 2 is a bottom perspective view thereof;

FIG. 3 is a rear perspective view thereof;

FIG. 4 is a side view thereof;

FIG. 5 is a top view thereof;

FIG. 6 is a bottom view thereof; and,

FIG. 7 is a front view thereof.

The areas within the dashed lines in FIG. 2 and FIG. 6 form no part of the claimed design.

The view opposite the side view of FIG. 4 is a mirror image thereof and, therefore, is omitted.
